M. DODGE,
AUTOMATIC FOOD AND PACKAGE CARRIER.
APPLICATION FILED MAY 11, 1921.

Patented Apr. 4, 1922.

UNITED STATES PATENT OFFICE.

MARTIN DODGE, OF WASHINGTON, DISTRICT OF COLUMBIA.

AUTOMATIC FOOD AND PACKAGE CARRIER.

1,411,845.

Specification of Letters Patent. Patented Apr. 4, 1922.

Application filed May 11, 1921. Serial No. 468,681.

To all whom it may concern:

Be it known that I, MARTIN DODGE, a citizen of United States, residing at Washington, District of Columbia, have invented certain new and useful Improvements in Automatic Food and Package Carriers, of which the following is a specification, reference being had therein to the accompanying drawing.

- 10 The present invention relates to transportation, and more particularly apparatus for conveying food stuffs, packages, mail and the like, and aims to provide a novel and improved carrier adapted especially for the 15 delivery of food or farm produce into the city or central station for consumption or distribution, and also adapted for use in delivering packages from the city or central station to the outlying or rural sections.
- 20 Another object of the invention is the provision of a light, simple and inexpensive carrier of that kind, which will have a minimum of dead weight, and which will be highly efficient for the conveyance of 25 commodities to or from a trading station or point at a minimum cost and time, thereby eliminating the present day high cost of deliveries by motor-driven or animal-drawn vehicles.

- 30 A further object is the provision of a novel and improved carrier designed to travel on an overhead rail, from which the carrier is suspended, and including a light and simple construction and a detachable 35 body or receptacle for holding the goods or objects to be transported.

- 40 A still further object is the provision of such a carrier including a body or receptacle detachably supported in a novel manner for the convenient attachment of the body to and detachment thereof from the wheeled frame or carriage which can remain on the rail.

- 45 With the foregoing and other objects in view, which will be understood as the description proceeds, the invention resides in the construction and arrangement of parts, as hereinafter described and claimed, it being understood that changes can be made 50 within the scope of what is claimed, without departing from the spirit of the invention.

The invention is illustrated in the accompanying drawing, wherein:

Figure 1 is a side elevation of the carrier. Fig. 2 is an end view thereof.

55 The carrier includes a pair of flanged wheels 3 to roll on an overhead rail 4, and said rail can be supported from the lattice frame or truss 5 which extends along the rail, and which includes a lower angle member 6 on the outstanding flange of which the rail 4 is secured in any suitable manner. The frame 5 is supported at intervals along its length by the cross arms 7 and 8 of supporting poles 9, and a rail can be located at 60 each side of the poles, for the travel of the carriers in opposite directions to and from a central or trading station.

65 The frame of the carriage which travels on the rail includes a tie bar 11 connecting the axles 10 of the wheels 3, hanger bars 12 suspended from said axles, and extending downwardly across the rail 4, and a longitudinal horizontal supporting bar 13 secured to the lower terminals of the hanger 70 bars 12. This frame is extremely light in weight, although sufficiently strong to sustain considerable weight.

75 The carriage has means for the self-propulsion thereof along the rail, and, as shown, 80 an electric motor 14 is supported on the bar 13 to furnish the driving power. Angle brackets 15 are secured to the opposite sides of the supporting bar 13 and form a base on which the motor can be conveniently secured. 85 The operative connection between the motor and wheels, as shown, includes an endless sprocket chain 16 trained around a sprocket wheel 17 secured on the armature shaft 18 of the motor 14 and around sprocket wheels 19 90 secured on the axles 10, thus providing an extremely simple means for driving the wheels 3 from the motor.

95 In order to furnish electrical current for the motor, a short trolley pole or arm 20 is pivoted, as at 21, to the motor, and has a trolley wheel 22 to engage and move under a trolley wire or rod 23 located under the rail 4, and preferably located within an inverted channel member 24 of insulating material, to insulate the trolley, and also protect it from short circuit when it rains or 100

- snows. The member 24 can be secured to the under surface of the angle member 6, and the trolley wire or rod secured within said member 24, and the trolley is connected to 5 one terminal of the motor, while the other terminal can be grounded to the frame and rail to complete the circuit. The trolley pole 20 is spring-pressed to hold the trolley wheel against the trolley wire, and said trolley pole can be swung down to prevent the movement of the carriage, such as when loading same or unloading, and the carriage is started by bringing the trolley wheel against the trolley wire.
- 10 The body or receptacle 25 of the carrier, as shown, is of cylindrical form, with its forward end pointed, to lessen the resistance, and said body can be of any suitable size and capacity. The body is suspended from 15 the carriage frame, and, for this purpose, bands 26 embrace the body, and bails 27 are pivoted to the bands, as at 28, to engage the frame. The body or receptacle 25 has an opening or mouth 29 at the top between the bands 26 for filling the body and removing the contents thereof. In order to support the body from the frame, the ends of the bar 13 project beyond the hanger bars 12 slightly, and have upper notches or seats 25 30 for the bails 27, which can be conveniently swung over said projecting ends of the bar 13 to drop into said notches or seats, in which event the bails 27 converge upwardly, to eliminate the longitudinal 35 swaying of the body from the frame. The bands 26 are therefore spaced apart longitudinally farther than the notches or seats 30 so that the bails or hangers 27 will be inclined oppositely when engaged with the 40 frame.
- Levers 31 are pivoted, as at 32, to the ends of the bar 13 beyond the notches or seats 30, and are normally disposed at one side of the bar 13 and project toward one 45 another under the bails 27. These levers 31 can be raised by hand for conveniently raising the bails 27 out of the notches or seats and off the ends of the bar 13, for convenience in detaching the body or receptacle 25 when it has reached its destination. Such levers can also be used for engaging the bails over the ends of the bar 13 in applying the body to the carriage frame.
- 55 By using the detachable body or receptacle, the bodies of the carriers can be used interchangeably, and can be detached from the wheeled frames or carriages for convenience in filling and emptying the bodies, 60 and the carriages can also travel on the rail without the bodies for return trips to haul additional loads, etc.
- The carrier can be stopped at its destination, by the termination of the trolley wire 65 23, to stop the motor 14, or the rail can be

inclined or other means provided for stopping the carrier, which need not be described or illustrated herein.

In order to prevent the possible lifting of either wheel 3 off the rail 4, and to prevent the wheels jumping off such rail, it is preferable to support rollers 33 from the hanger bars 12 to be disposed slightly below the member 24. Thus, when either wheel 3 is raised slightly, the roller 33 underneath will contact with the member 24, thereby preventing said wheel 3 from moving higher or transversely off the rail.

Having thus described the invention, what is claimed as new is:—

1. A carrier comprising wheels to travel on a rail, hanger bars suspended from said wheels, a supporting bar carried by said hanger bars, a receptacle below said supporting bar, and hangers pivotally connected to the receptacle to swing over and seat on said supporting bar. 80

2. A carrier comprising wheels to travel on a rail, and having axles, hanger bars suspended from said axles, a supporting bar carried by said hanger bars, a driving device mounted on said supporting bar for propelling the wheels, a receptacle below said supporting bar, and hangers pivotally connected to the receptacle to swing over 90 95 said supporting bar into engagement therewith.

3. A carrier comprising a wheeled frame to travel on a rail and having hanger bars and a supporting bar carried by the hanger bars, said supporting bar having its ends projecting beyond the hanger bars, and a receptacle detachably suspended from said projecting ends of the supporting bar. 100

4. A carrier comprising a wheeled frame 105 to travel on a rail and having hanger bars and a supporting bar carried by the hanger bars, the ends of the supporting bar projecting beyond the hanger bars, a receptacle, and hangers for the receptacle engageable 110 over said projecting ends of the supporting bar.

5. A carrier comprising a wheeled frame to travel on a rail and having hanger bars and a supporting bar carried by the hanger 115 bars, the ends of the supporting bar projecting beyond the hanger bars, a receptacle, and bails pivoted to the receptacle and engageable over said projecting ends of the supporting bar, said supporting bar having 120 seats to receive said bails.

6. A carrier comprising a wheeled frame to travel on a rail and to be suspended therefrom, said frame having opposite projecting portions, and a detachable receptacle 125 having pivoted hangers engageable removably over said projecting portions.

7. A carrier comprising a wheeled frame to travel on and be suspended from a rail, said frame having projecting portions with 110

seats, a receptacle, bails pivoted to the receptacle and engageable over said portions to enter said seats, and levers pivoted to said portions to engage under the bails and remove them from said seats and portions.

8. A carrier comprising a wheeled frame to travel on and be suspended from a rail, said frame having projecting portions, a

receptacle, hangers for the receptacle engageable over said portions, and means operable for removing said hangers off said portions. 10

In testimony whereof I hereunto affix my signature.

MARTIN DODGE.
